UNITED STATES PATENT OFFICE.

JOHN MINOR BOTT'S LEWIS, OF LYNCHBURG, VIRGINIA.

ROD OR PIPE COUPLING.

1,322,801.

Specification of Letters Patent. Patented Nov. 25, 1919.

Application filed September 27, 1918. Serial No. 255,951.

To all whom it may concern:

Be it known that I, JOHN M. B. LEWIS, a citizen of the United States, residing at Lynchburg, in the county of Campbell and State of Virginia, have invented certain new and useful Improvements in Rod or Pipe Couplings, of which the following is a specification.

My invention relates to coupling means for connecting angularly arranged elements, such as tubes or rods.

An important object of the invention is to provide means of the above mentioned character, which are strong, durable, and attractive in appearance.

A further object of the invention is to provide means of the above mentioned character, having the operating parts thereof arranged within the tube to be coupled to another element or tube.

A further object of the invention is to provide coupling means of the above mentioned character, which may be manipulated in a highly convenient and expeditious manner.

Other objects and advantages of the invention will be apparent during the course of the following description.

In the accompanying drawings forming a part of this specification and in which like numerals are employed to designate like parts throughout the same,

Figure 1 is a longitudinal sectional view taken on line 1—1 of Fig. 2,

Fig. 2 is a similar view taken at a right angle to the showing of Fig. 1,

Fig. 3 is a view similar to Fig. 1, with the clamping elements released and shifted to the outer position,

Fig. 4 is a horizontal sectional view taken on line 4—4 of Fig. 2,

Fig. 5 is a side elevation of a double coupling, parts being shown in section, and,

Fig. 6 is a horizontal section taken on line 6—6 of Fig. 5.

In the drawings, wherein for the purpose of illustration is shown preferred embodiments of my invention, attention being called first to Figs. 1 to 4 inclusive, the numerals 10 and 11 designate angularly arranged elements to be connected, the same being shown disposed at a right angle. These elements are shown as tubes, while of course the invention is in no sense restricted to this precise construction.

My improved coupling embodies a pair of

oppositely arranged jaws 12, which are longitudinally curved, for the reception of the element 11, and extend beyond its center, as shown. The jaws 12 carry shanks 13, which are tapered, having straight inner faces 14, and longitudinally tapered outer faces 15, which are curved in cross-section. The jaws 12 form with the outer ends of the shanks 13, shoulders 16, which pivot upon the outer end of the tube 10, as shown. The numeral 17 designates an expanding element, shown as a smooth pin or bolt, while the invention is in no sense restricted to this construction. This expanding element passes through openings 18, formed in the tube 10, and a cotter-pin 19 is passed through a transverse opening 20 in the pin 17, holding it against longitudinal displacement. The expanding element or pin 17 is adapted to be forced within and through tapered openings 21, formed in the inner faces of the shanks 13, thereby moving the shanks outwardly, and causing them to turn upon the shoulders 16, as pivots. The recesses 21 are curved in cross-section, and are thereby adapted for the reception of the expanding element 17, the expanding element also serving to prevent longitudinal displacement of the shanks 13 with respect to the tube 10.

In assembling this form of my invention, the jaws 12 are first placed upon opposite sides of the element 11, and the shanks 13 inserted within the end of the tube 10. The transverse pin 17 is now passed through the openings 18 and the tapered recesses 21, thereby swinging the shanks outwardly and the jaws 12 inwardly, into clamping engagement with the upper element 11. It is thus apparent that the shanks 13 are locked against longitudinal movement with relation to the tube 10 and the jaws 12 rigidly connect the elements 10 and 11.

A double coupling is shown in Figs. 5 and 6, wherein the numeral 22 designates an element or tube, and 23 elements or tubes, arranged at a right angle thereto and upon opposite sides thereof.

The double coupling comprises pairs of jaws 24 and 25, longitudinally curved for the reception of the element 22, and extending in opposite directions past its center, as shown. The jaws of the opposite pairs interfit, and are provided with teeth 26, for this purpose.

Each pair of jaws has connection with shanks 27, similar to the shanks 13. These shanks project into the tube 23, and are held therein by a transverse expanding element 28, similar to the element 17. The element 28 extends through openings 29, and tapered recesses 30, formed in the shanks 27, the shanks turning upon shoulders 31.

In view of the foregoing description it is 10 thought unnecessary to state the mode of assembling of this form of the invention, as it is similar to that described in connection with the first form of the invention.

It is to be understood that the forms of 15 my invention herewith shown and described are to be taken as preferred examples of the same, and that various changes in the shape, size, and arrangement of parts may be resorted to without departing from the 20 spirit of the invention or the scope of the subjoined claims.

Having thus described my invention, I claim:

1. The combination with a tube provided 25 near its end with a transverse opening, of an element arranged at an angle near the end of the tube, a pair of jaws adapted to receive therebetween the element and carrying shanks projecting into the end of the 30 tube, and an expanding element extending through the transverse opening of the tube and contacting with the shanks to force them apart.

2. The combination with a tube provided 35 near its end with a transverse opening, of an element arranged at an angle near the end of the tube, a pair of jaws adapted to receive therebetween the element and carrying shanks projecting into the end of the 40 tube, said shanks being provided upon their inner faces with recesses, and an expanding element extending through the transverse opening of the tube and passing between the shanks to enter the recesses thereof to spread 45 the shanks and lock them against longitudinal displacement.

3. The combination with a tube provided 50 near its end with a transverse opening, of an element arranged at an angle near the end of the tube, a pair of jaws adapted to receive therebetween the element and carrying shanks projecting into the end of the tube, said shanks being provided upon their inner faces with longitudinally tapered recesses, and an expanding element extending 55 through the transverse opening of the tube

and arranged between the shanks and within the tapered recesses.

4. The combination with a tube, of an element arranged at an angle near the end of the tube, a pair of jaws adapted to receive therebetween the element and carrying shanks projecting into the end of the tube with the outer ends of the shanks contacting with the end of the tube to turn thereon as a pivot, and means to move the shanks away from each other.

5. The combination with an element having a tubular end, of a second element arranged near the tubular end and at an angle thereto, a swinging jaw to engage the second named element and having a shank projecting into the tubular end, the outer end of the shank engaging the tubular end and turning upon the same as a pivot, an expanding element passing transversely through the tubular end and engaging with the shank to move it in an outwardly direction, and a coacting jaw connected with the tubular end to engage with the second 80 named element.

6. The combination with an element having a tubular end, of a second element arranged near the tubular end and disposed at an angle thereto, a swinging jaw arranged to engage the second named element and provided with a tapering shank projecting into the tubular end, the outer end of the shank contacting with the tubular end and turning upon the same at a pivot, said shank being provided with a tapered transverse recess, an expanding element extending transversely of the tubular end and adapted to operate within the tapered recesses, and a coacting jaw carried by the tubular end and 95 engaging the opposite side of the second named element.

7. In apparatus of the character described, oppositely arranged pairs of jaws adapted to receive and hold an element, the 100 jaws having interfitting teeth which extend beyond the center of the element, shanks secured to the jaws in each pair and adapted for insertion within a tube, and means to move the shanks away from each other. 105

In testimony whereof I affix my signature in presence of two witnesses.

JOHN MINOR BOTT'S LEWIS.
